UNITED STATES PATENT OFFICE.

HERBERT R. KEITHLEY, OF BUFFALO, NEW YORK.

EXCAVATOR.

SPECIFICATION forming part of Letters Patent No. 564,696, dated July 28, 1896.

Application filed June 14, 1895. Serial No. 552,757. (No model.)

To all whom it may concern:

Be it known that I, HERBERT R. KEITHLEY, of Buffalo, in the county of Erie and State of New York, have invented certain new and 5 useful Improvements in Excavators; and I do hereby declare that the following is a full, clear, and exact description thereof, reference being had to the accompanying drawings, and to the letters of reference marked thereon, 10 which form a part of this specification.

This invention relates to improvements in that class of excavating-machines in which a vertically-reciprocating cutter, spade, or plow is employed to cut successive perpendicular 15 sections of earth from the end or side walls of the trench or ditch.

The object of the invention is to provide an improved construction in devices of the character referred to; and it consists in the matter 20 herein set forth and particularly pointed out in the appended claims.

In the accompanying drawings, Figure 1 is a sectional side elevation of an excavating-machine constructed in accordance with my 25 invention. Figs. 2 and 3 are transverse sectional elevations taken on lines 2 2 and 3 3, respectively, of Fig. 1.

In said drawings, A and B designate, respectively, a boiler and engine of any suitable or preferred type mounted upon a portable frame or truck C, the wheels c of which run upon longitudinal truck-rails D, that are laid along the opposite sides of the trench or ditch to be excavated. As herein shown, said 30 truck is composed of upper and lower side beams C' and C², uprights C³, C⁴, and C⁵, and upper and lower transverse connecting-beams C⁶ and C⁷.

E designates a vertically-reciprocating cutter or plow which is secured to the lower end of an upright rack-bar F. Said cutter has a sharpened or chisel-like edge and is preferably made of wedge shape in vertical cross-section with a rearwardly-projecting 40 share or blade e, adapted to force the dirt rearwardly as the cutter penetrates the ground. The reciprocating rack or cutter bar F is guided at its upper portion between the upper transverse connecting-beams C⁶ and rests 45 against and is guided at its lower portion by the lower connecting-beam C⁷. As herein shown, said rack-bar is composed of two par-

allel side bars f and a series of horizontal cross-bolts or trundles f', which connect said side bars and form the teeth of the rack. The 55 rack-bar F and attached cutter E are arranged to be raised and lowered by means of a transverse shaft G, which is suitably journaled upon the upper side beams C', and is provided with a pinion G', that intermeshes with the 60 teeth f' of the rack-bar. The shaft G is herein shown as actuated by a counter-shaft J, having at one end a pinion J', which intermeshes with a second gear G² on the shaft G, said counter-shaft having at its opposite end a 65 pulley J², which is connected with the driving-pulley B' of the engine by a belt J³.

L designates a horizontally-arranged lever mounted between its ends upon a horizontal pivot l, with its rear end in close proximity to 70 the rack-bar F, its front end being connected by a link l' with the throttle-lever B² of the engine. The rear end of the lever L is adapted for alternate engagement with upper and lower stop-lugs f² and f³ on the rack-bar 75 F. As herein shown, the upper stop is formed by the end of an adjustable screw-bolt carried by a forwardly-projecting lug f⁴ on the upper end of the rack-bar, while the lower stop f³ consists of a transverse bolt extending 80 between the side bars f, near the lower end of the same. With this construction, when the rack-bar reaches the extremity of either its upward or downward movement, one of the stops f² or f³ will operate through the 85 lever L to oscillate the throttle-lever and stop the engine. The engine is started in the opposite direction to reverse the direction of movement of the cutter by the engineer or attendant. The stop f³ being beneath the 90 lever L and at the lower limit of its movement when the engine is started to lift the cutter, said cutter will rise until the said stop reaches and moves the said lever and the engine is thereby stopped. The action of the 95 upper stop f² in the descent of the cutter is similar. The depth to which the cutter will be driven, or, in other words, the depth of the trench or ditch, will obviously depend upon the point at which the engine is reversed by 100 the stop-screw f², and may readily be controlled as desired by adjusting said screw up or down. The opposite ends of the lever L are herein shown as offset laterally to avoid

interference with the boiler A, said ends being made of separate pieces rigidly connected together by the pivot l of the lever. Obviously, however, the operation of the device is the same as though said lever were made of a single continuous piece.

M designates a traveling shield mounted on the truck C behind the cutter E and rack-bar F, and comprising parallel side plates M', which engage and support the opposite side walls of the trench, so as to prevent the same from falling in. Said shield is adjustably supported between the side beams of the truck, so as to be capable of being raised or lowered in accordance with the depth of the trench to be excavated, and in this instance is shown as pivotally supported upon a transverse bar N, which extends through bearing-blocks m, located on the upper edges of the side plates M', about midway of the length thereof. The bar N is provided at its ends with enlarged heads n, which have screw-threaded engagement with vertical adjusting-screws N', so that when the latter are rotated the bar N and shield M will be raised or lowered accordingly. The screws N' rest at their lower ends in conical sockets formed in bracket-castings n', which are bolted to the lower side beams C² of the truck, while the upper ends of said screws press through bearing-apertures in longitudinal bars C³, which connect the upper ends of the uprights C⁴ and C⁵ at each side of the frame. The screws N' are adapted to be rotated by rigidly-attached collars n², having a plurality of peripheral apertures n³, in which the end of an actuating bar or spanner may be inserted. The side plates M' are held apart against the inward pressure of the walls of the trench by transverse struts M², which consist of two separate ends or sections which have a telescopic screw-threaded engagement with each other, by means of which said struts may be adjusted in length to provide for trenches of greater or less width.

O designates a second and horizontally-arranged cutter extending transversely between the side plates M', at the lower front corners thereof. As herein shown, said cutter consists of a wedge-shaped blade o, the lower surface of which is adapted to rest upon the bottom of the trench and the cutting edge o' of which faces forwardly and is in this instance located in the same plane with the front edges m' of the side plates M', said edges m' of the side plates being also herein shown as sharpened to a cutting edge. At its ends the cutter O is provided with lateral flanges o², which engage and are rigidly bolted to the inner face of the side plates M', and, as shown in this instance, the cutter is still further secured by stops o³, which are secured to the flanges o and embrace the adjacent transverse strut M². The cutter O is designed to cut through the lower end or base of each section of earth after the latter is cut down by the vertically-reciprocating cutter E, and to

this end the said cutter O, together with the shield M, is forced forward after each stroke of the cutter E far enough to detach said earth section. Such forward movement of the cutter and shield is, as a further improvement, herein shown as accomplished by a hydraulic ram P, mounted on the shield M at the lower rear portion thereof. Said ram comprises a cylinder P', provided with a piston p, the piston-rod p' of which projects out through the rear head of the cylinder and is adapted to react against a stationary cross-bar Q, or any other fixed abutment, to force the shield forward. The front end of the cylinder P' is connected by a supply-pipe P² with the discharge-chamber of a pump R, which in this instance is an ordinary steam-pump located on the truck C in proximity to the rest of the operating machinery. The discharge from the cylinder P' takes place through a valved passage p², which connects the front end of said cylinder with a subjacent tank P³, the latter being in turn connected with the suction-chamber of the pump R by a pipe P⁴. The valve p³ of said discharge-passage p² is arranged to open automatically when the piston p reaches the outer limit of its stroke, and to this end is provided with a radial arm p⁴, to which a rearwardly-extending link p⁵ is attached. The rear end of said link extends beneath the outer or rear end of the piston-rod p', and the latter is provided at its extremity with a downwardly-projecting rigid arm p⁶. A lateral stud or pin p⁷ projects from the lower end of the arm p⁶ through a slot p⁸ in the link p⁵, and is arranged to engage the rear end of said slot and open the valve p³ just as the piston reaches the end of its outward stroke.

As herein shown, the ram P is adjustably supported between vertical side bars P⁵, which are mounted upon the adjacent struts M² of the shield, said bars P⁵ being provided with vertical slots p⁹, which are adapted to be engaged by clamping-bolts p¹⁰ on the ram. When said bolts p¹⁰ are loosened, the ram is arranged to be raised or lowered as desired by means of vertical adjusting-screws p¹¹ and p¹², which are mounted in lateral lugs p¹³ and p¹⁴, that project from the ends of the side bars P⁵. The supply and discharge pipes P² and P⁴ are provided with flexible sections p¹⁵ and p¹⁶, by reason of which the raising and lowering of the ram on the shield or of the shield in the frame does not interfere with its connections with the pump. Said pump R is arranged to be alternately thrown into and out of operation by means of the same stop-pin f³ which serves to oscillate the lever L in the upward movement of the cutter E, the construction to this end being as follows:

r designates a bell-crank lever provided at its rear end with a bifurcated fork r'. The upper end of the bell-crank is attached by a link-bar r² with the throttle R' of the pump, so as to alternately open and close the latter as the bell-crank lever is oscillated. The

stop-pin f^3 enters the bifurcated end of the bell-crank lever just as the cutter E is raised clear of the ground, and after oscillating said lever, so as to admit steam to the pump, continues its upward movement until it strikes the lever L and stops the engine in the manner before described. The starting of the pump forces water through the pipe P^2 to the cylinder P' of the ram and causes the piston 10 of the latter to move rearwardly to the limit of its stroke. Said piston is of course prevented from actual movement with respect to the ground by the cross-bar or abutment Q, against which the outer end of the piston-rod 15 rests, and the reaction of the piston on the ram serves instead to force the latter forward, together with the shield M on which it is mounted. Said forward movement of the shield obviously forces the transverse cutter 20 O through the base of the earth section previously detached by the cutter E and leaves the same in condition to be readily removed. The forward movement of the shield is also in this instance utilized to force the entire 25 machine forward, such result being naturally produced by the forward pressure of the shield on its supporting-bar N due to the resistance offered by the earth to the advance of the cutter O. In order, however, to render 30 this operation more certain, said shield is herein shown as provided at its upper edge with adjustable wedges m^3 , which are adapted to engage a transverse bar m^4 , that is adapted to be inserted in any one of a vertical series 35 of apertures m^5 in the upright C⁴ of the frame. Said bar is placed in the nearest superadjacent aperture, after the shield is adjusted to the depth required, and the wedges are then forced forward by adjusting-screws m^6 until 40 they are brought into contact with said bar. By this construction it is obvious that the shield will be prevented from swinging forward on its supporting-bar N, and consequently the shield and frame will move forward together under the pressure of the ram P. As the piston of the latter reaches the outer limit of its stroke the valve p^3 will be opened in the manner before described and permit the water to pass downwardly into the 45 tank P^3 , thus relieving said piston from pressure. The piston-rod may then be forced back by an attendant and the timber Q moved forward in preparation for the succeeding stroke. The pump R in the meantime will 50 continue to operate until the stop-pin f^3 descends and by its engagement with the bifurcated end of the bell-crank lever r shuts off steam therefrom; but such operation will obviously merely cause the water to circulate 55 from the pump through the cylinder P' to the tank P^3 and from the latter back to the pump through the pipe P^4 . The piston-rod p' of the ram is herein shown as terminating at its outer end in an enlarged head p^{17} , by which 60 an ample bearing is afforded against the timber Q, and it will be understood that instead of moving the said timber after each forward

movement of the machine any suitable blocking may be inserted between the timber and the head of the piston-rod to afford the necessary positive resistance to the ram. 70

For the purpose of removing the earth detached by the cutters E and O, as hereinbefore described, the excavator is herein shown as provided with an endless carrier S, which 75 in this instance is formed by a sprocket-chain S', provided with two separate sets of buckets s. The buckets of each set are herein shown as two in number, and the two sets are so located on the sprocket-chain as to be separated from each other by the length of the carrier. The chain S' is mounted upon sprocket-wheels s^1 and s^2 , of which the former is supported upon a transverse shaft s^3 , located as closely above and to the rear of the cutter O 80 as will permit the passage of the buckets around the pulley. The upper sprocket-wheel s^2 is herein shown as supported upon a transverse shaft s^4 , carried between upwardly and rearwardly projecting bracket-arms s^5 , 85 which are bolted to the side plates M' of the shield. Said shaft s^4 is provided at its outer end with a driving-pulley S², which is connected with a pulley g^3 on the shaft G by means of a belt or sprocket-chain S³. A 90 backing-ratchet s^6 is inserted between the pulley S² and its shaft and is so arranged that the conveyer will be actuated only during the upward movement of the cutter E, and the location of the buckets on the chain is 95 such that the same will rest during their intermediate movement at the upper and lower ends of the conveyer in the positions shown in Fig. 1. 100

The discharge through the buckets s is received by a dump-car T, which, as herein shown, is arranged to travel upon tracks c', that extend upwardly and rearwardly over the trucks C and are rigidly connected therewith. Said car T is pulled up the incline by 105 a rope t, which passes over a pulley T' at the rear of said track and is wound on a drum G⁴ on the end of shaft G. The bottom T² of the car is shown as hinged at its front end to the body of the car and is supported 110 at its rear end by a wheel t², which runs upon a separate track c², placed between the tracks c' and extending parallel therewith near its rear end. Said inner track is inclined sharply 115 downward at its rear end, so that as the car reaches its rear end of its path of movement its bottom T² will swing down and discharge the load. The car is arranged to be drawn up the inclined tracks when the shaft G is rotated in a direction to drive the cutter E 120 downward and is permitted to descend by gravity as the rope t is unwound in the reverse movement of the shaft. At the time each set of buckets s reaches the upper limit of its movement and assumes the position 125 shown in Fig. 1, therefore, the car will have just reached the forward limit of its movement and will stand in position to receive the 130 contents of said buckets.

The excavating-machine thus described is particularly well adapted for use in excavating trenches of relatively great depth, such, for example, as those required in the laying 5 of sewers or similar pipes or conduits; but such machines may obviously also be employed in any other service for which they are deemed suitable.

I claim as my invention—

- 10 1. An excavating-machine comprising a main frame adapted to travel along the ground, a vertically-reciprocating cutter mounted in said frame, a shield rigidly secured in said frame and comprising opposite side plates adapted to engage and support the side walls of the trench, a transverse cutter rigidly secured between the lower front corners of said plates and means for advancing the entire machine after each 15 stroke of the reciprocating cutter, substantially as described.
- 20 2. In an excavating-machine the combination with a vertically-reciprocating spade or cutter, of a second and horizontally-movable cutter located at the bottom of the trench behind the vertical cutter, and means embracing a hydraulic-pressure device for forcing forward the second cutter, substantially as described.
- 25 3. In an excavating-machine the combination with a vertically-reciprocating spade or cutter of a shield provided with side plates adapted to engage and support the side walls of the trench behind said cutter, a second cutter 30 extending transversely between said side plates, and means embracing a hydraulic-pressure device for forcing forward said second cutter, substantially as described.
- 35 4. In an excavating-machine the combination with a vertically-movable spade or cutter, of a shield provided with side plates adapted to support the side walls of the trench behind said cutter, a second cutter extending transversely between the side plates at the 40 lower front corners thereof, and means embracing a hydraulic-pressure device for forcing forward the shield, substantially as described.
- 45 5. In an excavating-machine the combination with a vertically-movable spade or cutter, of a shield provided with side plates adapted to support the side walls of the trench behind said cutter, a second cutter extending transversely between the side plates at the 50 lower front corners thereof, and a hydraulic ram carried by said side plates and adapted to act against a stationary bar or abutment at the rear of the shield to force the latter forward, substantially as described.
- 55 6. In an excavating-machine the combination with a vertically-reciprocating spade or cutter, of a second and horizontally-movable cutter located at the bottom of the trench behind the vertically-movable cutter, means 55 for forcing forward the second cutter, and an endless conveyer extending upwardly from

the vicinity of said second cutter, substantially as described.

7. In an excavating-machine the combination with a vertically-reciprocating spade or cutter, of a shield provided with side plates adapted to engage the walls of the trench behind said cutter, a second cutter extending transversely between said side plates at the lower front corners thereof, means for forcing forward said shield, and an endless conveyer mounted between the side plates and extending upwardly from the vicinity of the second cutter, substantially as described.

8. In an excavating-machine the combination with a vertically-reciprocating spade or cutter, of a second and horizontally-movable cutter located at the bottom of the trench behind the vertically-movable cutter, means embracing a hydraulic-pressure device for 85 forcing forward the second cutter, and an endless conveyer extending upwardly from the vicinity of said second cutter, substantially as described.

9. The combination with a vertically-reciprocating spade or cutter, of a shield provided with side plates adapted to engage the walls of the trench behind the spade or cutter, a second cutter extending transversely between said side plates at the lower front corners 95 thereof, means embracing a hydraulic-pressure device for forcing forward said shield, and an endless conveyer mounted between the side plates and extending upwardly from the vicinity of the second cutter, substantially as described.

10. The combination with the vertically-reciprocating cutter, of a shield provided with side plates adapted to support the side walls of the trench behind said cutter, a second cutter extending transversely between the side plates at the lower front corners thereof, a hydraulic ram carried by the side plates and adapted to act against a stationary bar or abutment at the rear of the shield, and an 105 endless conveyer mounted between the side plates and extending upwardly from the vicinity of the second cutter, substantially as described.

11. The combination with a vertically-reciprocating cutter, and a second and horizontally-movable cutter mounted behind the first cutter and at the lower end of the path of movement thereof, of an endless conveyer extending upwardly from the vicinity of the 110 second cutter and means for intermittently actuating the conveyer during the upstrokes of the first cutter, substantially as described.

12. In an excavating-machine the combination with a vertically-reciprocating cutter, a 115 rack-bar secured thereto, a shaft provided with a pinion intermeshing with said rack-bar and means for rotating said shaft alternately in opposite directions, of an endless carrier for removing dirt from the trench, 120 driving and supporting wheels for said carrier, and driving connections including a 125

backing-ratchet between the rack-bar-actuating shaft and carrier-driving wheel, whereby said carrier is intermittently actuated during a part of each full reciprocation of the cutter, substantially as described.

13. In an excavating-machine the combination with a vertically-reciprocating cutter, a rack-bar secured thereto, a shaft provided with a pinion intermeshing with said rack-bar, and means for rotating said shaft alternately in opposite directions, of an endless carrier for removing dirt from the trench provided with two separated sets of buckets, driving and supporting wheels for said carrier, and driving connections including a backing-ratchet between the rack-bar-actuating shaft and the carrier-driving wheel, substantially as described.

14. In an excavating-machine the combination with a vertically-reciprocating cutter of a second and horizontally-movable cutter located at the bottom of the trench behind the vertical cutter, a hydraulic ram for forcing forward said second cutter, a pump for operating said ram, and means for throwing said pump into and out of operation in each reciprocation of the first cutter, substantially as described.

15. In an excavating-machine the combination with a vertically-reciprocating cutter, of a second horizontally-movable cutter located at the bottom of the trench behind the vertical cutter, a hydraulic ram for forcing forward said second cutter, a pump for operating said ram, an oscillatory lever connected with the throttle-valve of the pump, and a stop attached to the vertically-movable cutter adapted to oscillate said lever, substantially as described.

16. In an excavating-machine the combination with a vertically-reciprocating cutter, of a second and horizontally-movable cutter located at the bottom of the trench behind the vertical cutter, a hydraulic ram for forcing forward said second cutter, said ram comprising a hydraulic cylinder and supply-pipe opening into one end of said cylinder, a discharge-passage opening out of the same end of the cylinder, a valve controlling said discharge-passage, means for opening said valve when the piston reaches the outer end of its stroke, and means for supplying water under pressure to said cylinder, substantially as described.

17. An excavating-machine provided with a horizontally-movable cutter, a hydraulic ram for forcing forward said cutter, said ram comprising a cylinder and piston, a supply-pipe entering at one end of the cylinder, a valved discharge-passage opening out of said cylinder into a subjacent tank, a piston-rod projecting from the cylinder, a valve-operating link extending from the discharge-valve toward the outer end of the piston-rod, a projection on said piston-rod engaging a slot in said link whereby the discharge-valve is opened at the end of the outward stroke of the piston, and a pump provided with discharge and suction chambers connected respectively with the supply and discharge ports of the hydraulic cylinder, substantially as described.

18. In an excavating-machine the combination with a reciprocating spade or cutter of an engine for actuating said cutter and means for automatically stopping the engine when the cutter reaches the limit of its movement in each direction, substantially as described.

19. In an excavating-machine the combination with a reciprocating spade or cutter of an engine for actuating said cutter, operative connections with the throttle-valve of the engine and means connected with the cutter for moving said operative connections to close the throttle-valve when the cutter reaches the limit of its stroke in each direction, substantially as described.

20. In an excavating-machine the combination with a reciprocating spade or cutter and a rack-bar secured thereto of a pinion intermeshing with said rack-bar, an engine for rotating said pinion alternately in opposite directions, stops on said rack-bar, an oscillatory lever projecting into the path of said stops and connections between the lever and the throttle-valve of the engine whereby the latter is closed when the cutter reaches the limit of its movement in each direction, substantially as described.

In testimony that I claim the foregoing as my invention I affix my signature, in presence of two witnesses, this 13th day of June, A. D. 1895.

HERBERT R. KEITHLEY.
